UNITED STATES PATENT OFFICE.

JOSEPH LEGRIS AND EDGAR S. LEGRIS, OF BOURBONNAIS, ILLINOIS.

PORABLE CONVEYER.

1,073,054.

Specification of Letters Patent. Patented Sept. 9, 1913.

Application filed October 14, 1911. Serial No. 654,742.

To all whom it may concern:

Be it known that we, JOSEPH LEGRIS and EDGAR S. LEGRIS, citizens of the United States, residing at Bourbonnais, in the county of Kankakee and State of Illinois, have invented new and useful Improvements in Portable Conveyers, of which the following is a specification.

The invention relates to conveyers, and more particularly to the class of portable adjustable and knock-down conveyers.

The primary object of the invention is the provision of a portable conveyer which can be readily knocked down and folded into compact form for the easy and convenient transportation thereof.

Another object of the invention is the provision of a conveyer of this character in which the sections thereof are connected in a novel manner so as to permit the extending or contracting of the conveyer without the possibility of the separation of the sections.

A further object of the invention is the provision of a conveyer which can be quickly swung from one side to the other so that the cribs may be operated upon.

A still further object of the invention is the provision of a conveyer in which the horizontal sections may be vertically adjusted at either or both ends as may be required.

A still further object of the invention is the provision of a conveyer which is simple in construction, light in weight, yet possessing the requisite strength, and that will be thoroughly reliable and efficient in operation, and inexpensive in manufacture.

With these and other objects in view, the invention consists in the construction, combination and arrangement of parts, as will be hereinafter more fully described, illustrated in the accompanying drawings, and pointed out in the claims hereunto.

In the drawings: Figure 1 is a fragmentary side elevation of a corn shelling machine, showing the conveyer constructed in accordance with the invention attached thereto. Fig. 2 is a top plan view of the horizontal crib section of the conveyer. Fig. 3 is a similar view of the horizontal crib section of the elevator crib section of the conveyer. Fig. 4 is a side elevation of the conveyer ready for transportation from one point to another. Fig. 5 is a vertical longi-

tudinal sectional view of the horizontal crib section of the conveyer. Fig. 6 is a similar view through the elevator crib section. Fig. 7 is a side elevation on enlarged scale of the hopper. Fig. 8 is an end elevation of the horizontal crib section, showing the sections thereof in retracted position when telescoping within the other. Fig. 9 is a fragmentary vertical longitudinal sectional view on an enlarged scale of one of the extensible sections of the horizontal crib. Fig. 10 is a fragmentary side elevation of the inner extensible section of the horizontal crib. Fig. 11 is a fragmentary side elevation of one of the removable side board supporting brackets, showing the side board connected to one of the extensible sections of the horizontal crib. Fig. 12 is a fragmentary side elevation, showing the front end of the horizontally disposed crib lowered, with the front draft rigging detached therefrom. Fig. 13 is an elevation of the gear for operating the crib sections in unison. Fig. 14 is a vertical longitudinal sectional view through the hopper, showing the gear driving connection between the corn sheller and the elevator crib. Fig. 15 is a perspective view of the rack frame. Fig. 16 is a perspective view of one of the brackets 132 detached.

Similar reference characters indicate corresponding parts throughout the several views of the drawings.

Referring to the drawings by numerals, 10 designates the frame of a corn shelling machine of any ordinary well-known construction, the frame being supported upon wheels 11, as usual, whereby it may be hauled from one point to another. Upon the frame is mounted a drum or cylinder 12, in which is arranged corn shelling mechanism of any approved type, the drum or cylinder 12 being formed with an inlet chute or mouth extension 13, into which is delivered the corn to be shelled and with which communicates a detachable and rotary delivery hopper, presently described.

The conveyer comprises an extensible horizontal crib section, and an elevator crib section, the extensible section serving as a wagon box for the transportation of the conveyer, and including frames 14, 15, 16 and 17, respectively, each comprising vertical side walls 18, closed bottom 19, and open top 20, the said side walls 18 being connected at the open top 20 by means of cross

braces 21, so as to prevent the lateral spreading or contraction of the said side walls of the frame. To the cross braces 21 of the frames 14 and 17, respectively, are fixed stationary brackets 22 carrying upwardly diverging side boards 23, while fixed to the side walls 18 of the sections 15 and 16 are vertically alining loop members 24, in which are engaged detachable brackets 25, carrying upwardly diverging side boards 26, the latter being removed when the said frames 15 and 16 are retracted or moved inwardly into the frame 14, the said frames being designed to telescope within the latter, in a manner presently described.

The frame 14 is of greater length than the other frames of the horizontal crib section, and at the inner ends of the side walls 18 thereof, on the outer faces of the same, are fixed metallic plates 27, which are bolted or otherwise secured thereto, the said plates being formed with outwardly extending studs 28, on which are journaled hook-like latches 29 which are adapted to lock with hook-like keepers 30 formed on the inner ends of the side walls 18 of the frame 17 for detachably connecting the said frames 14 and 17, together, when the frames 15 and 16 have been telescoped within the frame 14. Formed on the plates 27 are bearing lugs 31 which are adapted to engage with and overlap bearing lugs 32 formed on the side walls of the frame 17, thus serving to prevent the vertical displacement of the frames 14 and 17 when connected together. The outer ends of the frames 14 and 17 are closed by means of vertical end walls 33. On the outer end of the frame 17 and rising from the side walls 18 thereof are substantially 40 goose-neck shaped extensions 34 formed with bearing terminals 35, with which align further bearings 36 formed on and projecting outwardly from the side walls 18 of the said frame 17, and in these bearings are 45 fixed vertical guide rods 37 embraced by the sleeve terminals 38 of the limbs 39 of a caster supporting bracket, the limbs 39 converging toward each other and being formed with a centrally located sleeve 40, in which 50 is journaled the stem 41 of a turning fork 42 supporting a rear guide wheel or caster 43. The stem 41 has threaded thereon a lock nut 44 of the usual form, the sleeve terminals 38 of the limbs 39 of the bracket being slidably engaged with the rods 37, so that the wheel 43 may be vertically adjusted, in a manner presently described.

Journalized transversely in the limbs 39 of the bracket is a turning shaft 45 provided 60 with pinions 46, meshing with rack gears 47 loose upon a shaft 48 journalized in the sleeve terminals 38, the gears 47 meshing with stationary racks 49 fixed to the front wall of the frame 17. Thus it will be seen 65 that upon turning the shaft 45, the bracket

supporting the wheel 43 may be vertically adjusted for the raising and lowering of the front end of the horizontal crib section.

Fixed to the inner faces of the side walls 18 of the frames 14 and 15, and also the bottoms 19 and cross braces 21 thereof, are the supporting bases 50 of friction rollers 51 which permit the free telescoping of the frames 15 and 16, without binding thereof, when the same are moved inwardly into the frame 14, as will be apparent. Fixed to the inner faces of the side walls 18 of the frames 14, 15 and 16 are forwardly inclined guide tracks 52, the outer ends of which are formed with loops 53, in which engage friction rollers 54 fixed exteriorly of the side walls 18 of the frames 15 and 16, said rollers 51 being adapted to travel upon the guide tracks 52 on the telescoping of the said frames in the frame 14, but when the rollers 54 are engaged in the loops 53, the frames will be prevented from pulling apart when in upstanding position. Mounted at the upper edges of the side walls 18 of the frames 14, 15 and 16 are pivoted trip latches 55, which are adapted to drop into position when the rollers 54 are engaged in the loops 53, and thereby intersect the path of movement of the rollers 54 to hold the frames locked in upstanding position. However, it will be seen that by raising the trip latches 55, the rollers will be freed for disengagement from the loops 53 of the guide tracks 52 for permitting the telescoping of the frames 15 and 16 in the frame 14 of the conveyer section.

Near the close end of the frame 17 and fixed to the inner faces of the side walls 18 thereof are notched racks 56, in which are engaged the ends of a cross connecting rod 57 of a rack frame 58, the same being provided with elongated slots 59, through which is passed a rotatable and supporting shaft 60 having loosely mounted thereon rack pinions 61 adapted to mesh with the rack teeth 62 formed on the frame 58, the said shafts being also provided with loose locking pinions 63 which engage the rack teeth 62 for holding the shaft 60 in adjusted position in the rack frame 58, for the tightening and loosening of an endless conveyer belt or apron 64 trained over a guide roller 65 supported by said shaft 60 between the rack frames, the belt being also trained over a guide roller 66 fixed to a shaft 67 journalized in the side walls 18 of the frame 14, at the forward end thereof, and upon this belt or apron is adapted to be poured the ears of corn to be conveyed thereby to the elevating mechanism of the conveyer, presently described.

Fixed to the outer or forward end of the frame 14 are vertical posts 68, to which are pivotally connected swinging arms 69 having pivoted thereto adjusting brackets 70

70

120

125

130

provided with elongated slots 71, in which are engaged locking bolts 72, and in this manner the arms may be held in adjusted position at the required angle. Mounted on the outer ends of the swinging arms 69 are forked coupling members 73 for the detachable connection of the horizontal crib section with the elevator crib section, presently described.

19 The elevator crib section comprises an inclined frame 74 provided with the usual side boards 75, the frame and side boards being extended at the lower ends thereof to form a receiving extension 76, disposed at an acute angle to the major portion of the frame, the said extension 76 being provided with a hopper-shaped mouth 77, into which is fed the corn ears from the conveyer belt or apron 64 in the horizontal crib section.

20 Jounaled transversely in the side boards
 75, both at the upper end of the frame 74
 and the extension end 76 of the elevator
 section, are shafts 78 and 79, respectively,
 having fixed thereto the usual guide rollers
 25 80, over which is trained an endless elevator
 apron or belt 81, the upper end of the frame
 communicating directly with the open end
 of a hopper body 82, rotatably and detach-
 ably engaged in the mouth end of the chute

30 13 of the corn shelling machine, the said
hopper being formed with an annular out-
turned flange 83 adapted to rest upon the
rim 84 of the open mouth of the chute 13,
the said flange and rim being provided with
35 suitable registering openings to receive a
securing pin 85 detachably held therein, for
the fastening of the hopper body 82 upon the
chute 13 of the corn shelling machine. This
hopper body 82 has fixed thereto a casting

40 86 provided with spaced bearings 87 and 88, respectively. In the bearings 88 is journaled a shaft 89, to one end of which is fixed a sprocket 90, over which is trained an endless sprocket chain 91, the same being also trained over a sprocket 92 fixed to one end of the shaft 78, the latter having fixed thereto a further sprocket 93, over which is trained a sprocket chain 94, the

same being also trained over a sprocket 95
50 journaled upon a stud shaft 96, projecting
outwardly from one side of the frame 74.
This sprocket 95 is in the nature of a double-
sprocket, so as to carry a further sprocket
chain 97 to be trained over the same, which
55 chain is also trained over a sprocket 98 fixed
to a shaft 99, the latter supported in a
forked bearing 100 mounted on the free ends
of horizontally disposed rearwardly extend-
ing beams 101 fixed to the side boards 75 of
60 the elevator frame 74, the said beams 101
being braced by vertical standards 102 fixed
to the extension end 76 of the said elevator
frame.

On the shaft 99 is a beveled gear 103
65 meshing with a beveled gear 104 on a shaft

105 vertically journaled in a fork 106 carrying a further beveled gear 107 meshing with a beveled gear 108 fixed to a shaft 109 journaled in the fork 106, the shaft 109 being provided with a sprocket 110, over which is trained an endless chain 111 which is also trained over a sprocket 111^a fixed to the shaft 67. Thus in this manner, the endless apron 64 will be driven simultaneously with the apron 81 in the horizontal and inclined cribs, respectively. The shaft 109 is adapted to be inserted in the forked couplings 73 for connecting the horizontal crib section to the elevator crib section, the forked couplings being provided with detachable locking pins 111^b which sustain the couplings connected with the shaft 105, so as to prevent the separation of the sections when connected.

On the detachment of the horizontal crib section from the elevator crib section, there is adapted to be engaged with or attached to the front end of the said horizontal crib section a draft rigging, comprising a front axle 114, on which are journaled front supporting wheels 115, the axle being engaged by depending bearings 116 of a cross supporting beam 117 formed with upturned ends 118, the frame 14, at its front end, being adapted to rest upon the beam 117, and the upturned ends 118 are perforated to receive fastening pins 119, which engage in perforations formed in keeper plates 120 fixed to the side walls 18 of the frame 14, at its front end. Fixed to the depending bearings 116 of the cross beam 117 are the limbs 121 of an inverted U-shaped bail or yoke 122, which is adapted to engage in the forked couplings 73 and is locked therein by means of the pins 111^b, as will be clearly seen. 115

Connected to the bearings 116 of the cross beam 117 is a forwardly extending draft pole 123, which is designed to be supported in substantially horizontal position, when the holding rod 124 is detachably connected to the said pole and loosely connected to the bail or yoke 122. Disposed at opposite sides of the elevator frame 74 are posts 125, near the lower ends of which are fixed forwardly extending bearings 126, in which are journaled the stems or forks 127, in which are journaled caster wheels 128, the posts 125 being secured at their upper ends by means of a cross bar 129, while fixed to the lower 130

ends of the said posts 125 are plates 130, through which is passed a detachable tie rod 131. In this manner the posts 125 will be prevented from spreading apart.

5 Fixed to the side boards 75 of the elevator frame 74 are guide brackets 132, in which are loosely engaged the posts 125, the brackets being designed to limit the swinging movement of the posts during the raising and lowering of the elevator frame. Fixed 10 in the horizontal beams 101 are eye bolts 133, to which are fixed cables 134, the same adapted to be wound on and unwound from a windlass 135 fixed to a supporting shaft 15 136 journaled in bearings 137 mounted upon the posts 125, near the upper ends thereof. On one end of the shaft 136 is fixed a pulley wheel 138, over which is trained a band 139, the same being also trained over a pulley 20 wheel 140 journaled upon one of the posts 125, the said pulley 140 being provided with a turning crank 141 to be engaged by the operator for the turning of the pulley wheel 140, so that the cables 134 may be wound on 25 or unwound from the windlass, for the raising and lowering of the lower end of the elevator frame 74, as will be obvious. The endles

30 s

fore a detail description of the same has been omitted.

In the elevator section is arranged a roller 142, the same being disposed at the extension end thereof for guiding the lower 35 stretch of the conveyer belt 81. The roller 142 is mounted upon a shaft 143 provided with sliding bearings, said bearings being adjustable by means of follower screws 144 engaged in plates 145 fixed to the sides of 40 the elevator section, it being understood of course that the sides are slotted to accommodate the sliding bearings supporting the said roller 142, so that the latter may be adjusted for tensioning the conveyer belt or 45 apron 81 as desired. Engaged with the upper stretch of the conveyer belt or apron 81 are guide members 146 which cause the belt or apron 81 to present a curvature at the proper point between the extension 76 and 50 the major portion of the frame 74 of the elevator section.

What is claimed is:

1. In a conveyer, a horizontal crib section including a plurality of extensible sections, means locking the sections in extended relation to each other, means for vertically adjusting one end of said horizontal crib section, an endless conveyer apron mounted for travel in said crib section, means for tightening the said apron, means on one of the sections of the crib section for receiving the apron on retracting the said sections, and means for locking the sections in retracted relation to each other. 55

2. In a conveyer, a horizontal crib section including a plurality of extensible sections, means locking the sections in extended relation to each other, means for vertically adjusting one end of said horizontal crib section, an endless conveyer apron mounted 70 for travel in said crib section, means for tightening the said apron, means on one of the sections of the crib section for receiving the apron on retracting the said sections, means for locking the sections in retracted 75 relation to each other, and means for raising the other end of the horizontal crib section.

3. In a conveyer, a horizontal crib section including a plurality of extensible sections, 80 means locking the sections in extended relation to each other, means for vertically adjusting one end of said horizontal crib section, an endless conveyer apron mounted for 85 travel in said crib section, means for tightening the said apron, means on one of the sections of the crib section for receiving the apron on retracting the said sections, means for locking the sections in retracted relation to each other, means for raising the 90 other end of the horizontal crib section, and ground wheels journaled in the said vertically adjustable means and also journaled in the last-named means. 95

In testimony whereof we affix our signatures in presence of two witnesses.
